(Cl. D9—6)

To all whom it may concern:

Be it known that I, Herman Siemund, a citizen of the United States and resident of Chicago, Illinois, have invented a certain new, original, and ornamental Design for a Combined Handle Socket and Floor Scraper Holder, of which the following is a specification, reference being had to the accompanying drawing, forming part thereof, in which:

Fig. 1 is a top plan view of the combined han-

dle socket and floor scraper holder embodying my new design;

Fig. 2 is a side elevational view thereof;

Fig. 3 is a bottom plan view thereof;

Fig. 4 is a front elevational view thereof;

What I claim is:

The ornamental design for a combined handle socket and floor scraper holder, substantially as shown.

HERMAN SIEMUND.
